DISPENSER FOR BOBBY-PINS AND THE LIKE

John George Karasevich, Winnipeg, Manitoba, Canada

Application December 14, 1955, Serial No. 553,148

4 Claims. (Cl. 132—1)

The invention relates to a dispenser for Bobbie pins and the like, as described in the present specification and illustrated in the accompanying drawings that form a part of the same.

The invention consists essentially of the novel features of construction as pointed out broadly and specifically in the claims for novelty following a description containing an explanation in detail of an acceptable form of the invention.

The objects of the invention are to devise a receptacle-type dispenser for Bobbie pins from which the pins are automatically ejected one by one and which, during the ejection of the single pin, pre-sets the pin prongs the desired distance apart for placement of the pin in the hair, causing it to automatically close when positioned to the hair; to furnish a dispenser in which a number of Bobbie pins may be stored in their ordinarily closed condition and which automatically ejects a single pin in proper open condition for placement in the hair, closing the same when in place; to provide a Bobbie pin dispenser of a compactness enabling it to be easily and handily carried in a purse or handbag; to eliminate the necessity of personal handling of Bobbie pins when placing them in the hair, thus avoiding loss of time and annoyance caused by opening and closing the pin with the fingers or nails; to construct a Bobbie pin dispenser consisting of comparatively few mechanical components, one adapted for manufacture in a variety of suitable materials and that is simple in its operation; and generally to provide a dispenser for Bobbie pins and the like that is attractive in appearance and efficient for its purpose.

In the drawings:

Figure 1 is a perspective view of the dispenser.

Figure 2 is a perspective view of the dispenser having the lid open and showing the compartment for the pins.

Figure 3 is a perspective view of the flanged base plate of the dispenser and illustrating the operating lever mounted therein.

Figure 4 is a longitudinal sectional view as taken along the line 4—4 in Figure 1.

Figure 5 is an enlarged fragmentary detail, in perspective, showing the manner in which the free ends of the Bobbie pin are spread as it is being ejected from the case.

Figure 6 is an enlarged fragmentary perspective detail showing the manner in which the Bobbie pin is ejected from the dispenser in its spread position.

Figure 7 is a perspective detail of the pressure bar.

Figure 8 is a fragmentary perspective detail of the pin supporting member and illustrating the pins mounted thereon.

Like numerals of reference indicate corresponding parts in the various figures.

Referring to the drawings, the dispenser, as indicated by the numeral 10, consists of a base plate having an elongated portion 11 at one end and an enlarged portion 12 at the other end, the two end portions being joined together by a narrow neck portion 13.

The base plate is provided with a flange 14 extending

2

around its contour with the exception of the open recess 15 or cut out which is formed by the neck and end portions.

The cover plate 16 is similarly shaped as the base plate but does not necessarily need to have the flange and this cover plate is secured to the base plate by the screws or other fastening means 17. In this manner the base plate and the cover plate form the handle 18 and the pin ejection compartment 19.

These plates may be made of any suitable material, such as plastic, metal or the like and which may be easily molded, pressed or otherwise fashioned to form the comparatively narrow handle and the wider and outwardly tapered pin ejection compartment.

A manually operated pressure rod or lever 20 has its inner end portion contained in the handle 18 and is provided with a slot 21 located at its inner or left extremity and which is engaged by the roller pin 22 and held under spring tension such as a snap spring 23.

The pressure spring lever projects from within the handle 18 across the opening or recess 15 and into the pin ejection compartment 19 at a slight outward or upward angle, the inner end walls of the handle and the pin ejection compartment being provided with apertures or slots permitting the lever free movement when pressed on.

The pressure rod is provided with a finger saddle 24 and which is so located as to be moved with the rod in and out of the opening or recess 15 of the dispenser and the ejection or piston 25 is firmly secured to the lever at the lever's right extremity.

The Bobbie pin compartment 26 is formed on the cover plate 16 above the location of the ejection pin compartment 19 and is provided with the end walls 27 and 28 and the side walls 29 and 30. These walls may be contiguous with one another and have outer flaring end recesses 31 and 32 that are parallel to one another and form an ejector or piston chamber and a pin ejection chamber, the latter having the ejection opening 33 for the Bobbie pin.

The ejector guide rail 34 is formed adjacent to the end of the pin compartment and leaving a space between itself and the end wall 28 of the pin compartment so as to form a space for the fixed spring 34A and is in direct alignment with the ejection opening 33 for the Bobbie pin.

The ejector guide rail terminates short of the side wall 30 and its free end is in contact with the fixed spring 34A. The purpose of the fixed spring is to act as a pressure guide for the rail so as to aid in guiding the pin into the ejection opening. After the pin has been ejected, the ejector or piston is automatically drawn back to its normal position, through the manual release of the rod or lever 20 and which is brought to its normal position by the spring 23. The pressure against the spring 34A is then diminished, allowing the spring to give sufficient resilient contact with the free end of the guide rail 34 so as to keep the same in alignment with the pin ejection opening.

The ejector member or piston 25 has a curled lip portion 35 that engages the underside of the ejector guide rail and overlaps the exposed edge thereof and is slideable therealong. The underside 36 of the ejector member forms the engagement and pressure means for ejecting the Bobbie pins 37 through the ejection opening 33, where the pin spreader block 38 projects from the free arcuate end of the fixed spring.

The pin pressure bar 39 extends across the Bobbie pin compartment and is movably secured under spring tension 40 to the end wall 27 of the pin compartment and maintains the pressure against the Bobbie pins that are mounted on the pin guide rod 41 for abutting contact engagement with the inner side of the guide rail 34.

The Bobbie pin compartment is provided with a hinged lid 42 having a suitable type latch or catch 43 for locking the lid to the compartment and has also the slot 43 along one side for removing the card supporting the pins from the compartment.

Access to the interior of the Bobbie pin compartment and the pin ejection portion is by lifting the lid 42, placing a card of Bobbie pins within the compartment and causing the pins to be engaged by the pin guide rod 41, removing the card and thus leave the pins in their guided position within the compartment.

Due to the spring pressure on the pressure bar the pins are kept under constant abutting contact with one another and always having the outermost pin in abutting contact with the inner surface of the guide rail so that each pin in succession will be located below the under surface of the ejector or piston 25 which engages with the guide rail 34 and acts as the means for ejecting the pin out through the pin ejection opening.

In using the dispenser, the person holds the unit to the portion of the head of hair to which they wish a Bobbie pin to engage, pressing on the finger saddle to move the lever, which being so mounted on the bearing or roller pin as to be given axial movement, permits the ejector member to move directly forward along the guide rail and force the individual Bobbie pin forward or across the pin compartment until the free ends of the Bobbie pin contacts the pin spreader block which is extended to the centre of the path by means of the spring to which it is fixedly secured. The forward movement of the Bobbie pin against the spreader block causes the same to open apart the prongs of the pin as it is forced along the guide rail towards the pin outlet where it emerges to contact the person's hair, the pin being now opened by the finger. As the pin is placed in position in the hair, the person releases pressure on the lever, the same being actuated by the lever spring to automatically move backwards and draw the ejector member back from the Bobbie pin and this coincidently allows the fixed spring and the pin spreader block to return to their normal position until the pin is brought back into position and ready for ejecting another pin when required.

It is of course understood that ramifications and modifications may be made without departing from the essential features of the invention as described and illustrated hereinabove.

What I claim is:

1. In a dispenser for Bobbie pins and the like, a base plate and a cover plate secured together and comprising a handle and a pin ejection compartment, said pin ejection compartment having a pin discharge aperture opening a Bobbie pin compartment formed on said cover plate and superimposed over said pin ejection compartment and having a passageway communicating therewith, a manually operated lever mounted in said handle and having a free end extending into said pin ejection compartment, a pin ejector secured to the free end of said lever and projecting into said pin compartment and adapted to engage with the pins individually fed thereto and eject the same from the pin compartment, an ejection guide rail having one end secured to the free end of said lever and extending into said pin ejection compartment, a spring member secured within said pin ejection compartment and adjacent to the pin discharge aperture opening thereof and adapted to be in contact with the free end of said ejection guide rail, and a pin spreader block secured to said spring member and located at the pin discharge opening of said pin ejection compartment.

2. In a dispenser for Bobbie pins and the like, a base plate having an elongated portion at one end and an enlarged portion at the other end, a narrow neck joining said portions together, a flange extending around the contour of said base plate with the exception of that portion of the contour of the base plate surrounding the

recess formed by said neck, a cover plate similarly shaped to said base plate and secured thereto, said base plate and said cover plate comprising a handle and a pin ejection compartment, said pin ejection compartment having a pin discharge aperture opening, a pin compartment superimposed over said pin ejection compartment and having a communicating passageway therewith, a manually operated lever mounted in said handle and having a free end extending into said pin ejection compartment, a pin ejector secured to the free end of said lever and projecting into said pin compartment and adapted to engage with the pins individually fed thereto and eject the same from the pin compartment, an ejection guide rail having one end secured to the free end of said lever and extending into said pin ejection compartment, a spring member secured within said pin ejection compartment and adjacent to the pin discharge aperture opening thereof and adapted to be in contact with the free end of said ejection guide rail, and a pin spreader block secured to said spring member and located at the pin discharge opening of said pin ejection compartment.

3. In a dispenser for Bobbie pins and the like, a base plate and a cover plate secured together and comprising a handle and a pin ejection compartment, said pin ejection compartment having a pin discharge aperture opening a Bobbie pin compartment formed on said cover plate and superimposed over said pin ejection compartment and having a communicating passage therewith, an ejector guide rail extending across the width of said Bobbie pin compartment and forming the outer end thereof, a manually operated lever mounted in said handle and having a free end extending into said pin ejection compartment, a pin ejector secured to the free end of said lever and engaging with said ejector guide rail and adapted to engage with the pins individually fed thereto and eject the same through the pin discharge aperture opening, a set spring secured to a wall of the communicating passageway between said Bobbie pin compartment and said pin ejection compartment and adapted to be in contact with the free end of said ejector guide rail, and a pin spreader block secured to said set spring and located at the pin discharge aperture opening of said pin ejection compartment.

4. In a dispenser for Bobbie pins and the like, a base plate, a cover plate secured to said base plate, a handle and a pin ejection compartment formed by said base plate and said cover plate and having a pin discharge aperture opening, a Bobbie pin compartment formed on said cover plate and superimposed over said pin ejection compartment and having a communicating passageway therewith and a pin discharge opening, a pin pressure bar located in said pin compartment and held in position therein and against the Bobbie pins by spring tension, an ejector guide rail extending across the width of said Bobbie pin compartment and forming the outer end thereof, a manually operated lever mounted in said handle and under spring tension and extending into said pin ejection compartment, a pin ejector secured to the free end of said lever and engaging with said ejector guide rail and adapted to engage with the pins individually fed thereto and eject the same through the pin discharge aperture opening, a set spring secured to a wall of the communicating passageway between said Bobbie pin compartment and said pin ejection compartment and adapted to be in contact with the free end of said ejector guide rail, and a pin spreader block secured to said set spring and located at the pin discharge aperture opening of said pin ejection compartment.
